No. 873,401.

PATENTED DEC. 10, 1907.

C. C. ABBOTT.

COUNTER CARRIER FOR VOTING MACHINES.

APPLICATION FILED MAY 20, 1907.

UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

COUNTER-CARRIER FOR VOTING-MACHINES.

No. 873,401.

Specification of Letters Patent.

Patented Dec. 10, 1907.

Application filed May 20, 1907. Serial No. 374,613.

To all whom it may concern:

Be it known that I, CHARLES C. ABBOTT, a citizen of the United States, residing at Pittsfield, county of Berkshire, State of Massachusetts, have invented a new and useful Counter-Carrier for Voting-Machines, of which the following is a specification.

This invention has for its object to provide a simple and inexpensive carrier for the counters of voting machines, which is adapted to be made entirely from sheet metal, thereby materially reducing the weight of the machine and effecting an important saving in the cost of the parts and in the expense of fitting.

With this end in view I have devised the simple and novel structure which I will now describe, referring to the accompanying drawing forming a part of this specification and using reference characters to indicate the several parts.

Figure 1 is a rear elevation of my novel carrier complete; Fig. 2 a plan view corresponding therewith; Fig. 3 a section on the line 3—3 in Figs. 1 and 2, looking in the direction of the arrows; and Fig. 4 is a detail elevation on an enlarged scale, illustrating the mode of attachment of the counters to the carrying bars.

In the present instance I have illustrated a carrier for a horizontal machine, although it will, of course, be obvious that the principle of the invention is equally applicable to a vertical machine.

10' denotes the carrying bars which are formed from strips of sheet metal preferably, although not necessarily, bent to substantially the form illustrated in the drawing. Each carrying bar comprises a vertical portion indicated by *a*, a horizontal portion indicated by *b*, a flange indicated by *c* which depends from the horizontal portion and a horizontal flange *d* which projects rearward from the top of the vertical portion.

11 denotes a counter (see Fig. 4). The counters rest upon the horizontal portion and are rigidly secured in any suitable manner to the vertical portion of the bars as by screws 12. In practice the carrying bars may be formed

50 from relatively light metal, ample strength and rigidity being secured by the flanges. The depending flange *c* is utilized in the identification of the counters by placing

thereon in alignment with each counter an identification mark, indicated by 13, which 55 enables the tabulators of votes to identify the individual counters at a glance; for example, B35, the letters indicating the lines of counters from top to bottom and the numbers the number of each counter in horizontal alignment counting from right to left as seen from the rear. The ends of the carrying bars are rigidly secured to end strips 14 which are formed from sheet metal bent to substantially U-shape. A part of the 60 horizontal portion and depending flange of each carrying bar is cut away at each end, leaving recesses indicated by 20 (see Fig. 1 in connection with Fig. 3), which receive the end strips. The edges of the horizontal 70 flanges and of the remaining portion of the horizontal portions bear upon the face of the end strips, thus leaving U-shaped portions at the ends of each carrying bar for attaching portions, said U-shaped portions being 75 indicated by 21 (see Fig. 3).

I have shown the carrying bars as secured to the end strips by means of bolts 15 which pass through the faces of the bars so that when the nuts 22 on the bolts are tightened 80 up, the engaging edges of the carrying bars will be drawn tightly against the face of the end strips, which are seated in the recesses, the attachment of the parts being thus made secure and the carrier as a whole made perfectly rigid. 16 denotes bearings which 85 inclose eccentrics 17 carried by eccentric shafts 18. The bearings are shown as provided with attaching plates 19 which are rigidly bolted to end strips 14.

As the counting operation and the mode of imparting motion to the eccentric shafts form no portion of the present invention, they have not been illustrated and will not be described. It is sufficient for the purposes 95 of this specification to state that the counters are all rigidly secured to the carrier and move with it, and that the counting operation of all counters that have been connected to a voting member is effected through 100 movement of the carrier, which is an endwise lateral oscillation in the horizontal plane, to perform the counting operation, and then a return oscillation to the normal position after the counters have been disconnected from 105 the voting mechanism.

Having thus described my invention, I claim:

1. A counter carrier consisting of a plurality of bars formed from sheet metal, each bar comprising a vertical portion, a horizontal portion, a horizontal flange depending from the horizontal portion and a horizontal flange, and end strips to which the bars are attached.
2. A counter carrier consisting of a plurality of bars formed from sheet metal, each bar comprising a vertical portion, a horizontal portion, a horizontal flange and a flange depending from the horizontal portion and provided with identification marks, and end strips to which the bars are attached.
3. A counter carrier consisting of a plurality of bars formed from sheet metal, each bar comprising a vertical portion, a horizontal portion, a flange depending from the horizontal portion and a horizontal flange, and U-shaped end strips also formed from sheet metal to which the bars are attached and which are provided with bearings, for the purpose set forth.
4. A counter carrier consisting of a plurality of bars each comprising a vertical por-

tion, a horizontal portion, a flange depending from the horizontal portion and a horizontal flange, a part of the horizontal portion and depending flange being cut away at each end of the bars leaving recesses, U-shaped end strips engaging said recesses, the edges of the horizontal flange and the remaining portion of the horizontal portion engaging the faces of the end strips, and bolts passing through the faces of the bars and the end strips whereby the parts are secured together.

5. The combination with a bar comprising a vertical portion, a horizontal portion, a horizontal flange and a flange depending from the horizontal portion and provided with an identification mark, of a counter resting on the horizontal portion and secured to the vertical portion in alignment with the identification mark.

In testimony whereof I affix my signature, in presence of two witnesses.

CHARLES C. ABBOTT.

Witnesses:

GEO. O. B. HAWLEY,
CHARLES H. PITNEY.
